UNITED STATES PATENT OFFICE.

JOHN F. REINERT, OF SOUTH ELGIN, ILLINOIS.

SAND-SETTLING BOX.

1,237,959.

Specification of Letters Patent. Patented Aug. 21, 1917.

Application filed May 28, 1917. Serial No. 171,392.

To all whom it may concern:

Be it known that I, JOHN F. REINERT, a citizen of the United States, and a resident of South Elgin, in the county of Kane and State of Illinois, have invented certain new and useful Improvements in Sand-Settling Boxes, of which the following is a specification.

This invention relates to the class of devices into which a body of water carrying sand in suspension, is discharged, and in which the water and sand become separated and from which the separated water and sand are, respectively, discharged.

And the objects of this invention are to obtain an apparatus into which a flow of water holding sand suspended thereby may be continuously discharged; an apparatus which will separate all the sand from the water by means of which it is delivered thereinto; which will continuously discharge water therefrom and which will automatically, and at intervals, discharge therefrom the wet sand which has been separated from the water, without discharging with said sand, any considerable quantity of water.

Additional objects are to obtain a sand settling box of the kind described which is economically made, durable, not liable to break, get out of order or clog up.

The separation of the water and sand in this apparatus is accomplished by gravity, as in many sand settling boxes heretofore well known in the art.

To those skilled in the art it is well known that a rapidly moving body of water will hold sand in suspension and carry it along therewith; and that when the flow or current of said body of water is checked and said water comes to rest the sand suspended therein will, by gravity, fall or settle through the water and be deposited on the bottom of the place or receptacle holding said water and sand.

I have illustrated an apparatus embodying this invention in the drawings accompanying this specification and forming a part hereof and in which—

Figure 1, represents an end elevation.

Fig. 2 a side elevation;

Fig. 3 a vertical section of the movable members of the apparatus, and

Fig. 4 a horizontal section on line 4—4

of Fig. 3, viewed in the direction indicated 55 by the arrows.

A character applied to designate a given part indicates said part throughout the several figures of the drawings wherever the same appears.

A represents a tank which is provided with a plurality of down spouts *a*. B represents a pipe or conduit which is arranged to discharge water, holding sand in suspension, into tank A. C, C, respectively, represent pipes or conduits, attached to the lower ends of down spouts *a*. D, D, represent bearings which are secured to the under side of tank A. E, E, represent combined settling and discharge spouts which 70 are pivotally mounted on the bearings D, by pintles or bolts *d* and leaves *D'*. F, F, represent members which are mounted on the combined settling and discharge spouts E, by bolts *f*.

The functions of member F are those of weighing beams and said member is supported at its outer end by brace G. *g* is a bolt joining member F and brace G. H, H, represent weights which are movably 80 mounted on members F, and *h*, *h*, represent set screws by means of which the weights are rigidly secured in an adjusted position on member F.

The upper end of the combined settling 85 and discharge spout E is closed, (see Fig. 4), and said closed end is provided with the annular flange *e* and passageway *e'*, (see Figs. 3 and 4). I represents a flexible tube or hose, the lower end of which is attached to the flange *e* and the upper end to the lower end of the down spout *a*. J are bands respectively provided with tightening bolts *j*, by means of which said tubes or hose are attached as recited. K are doors which are 95 pivotally mounted on the lower end of down spouts E by means of the castings *k*, *k'* and pintles *k''*. L represents a stationary member on which the links *M* are pivotally mounted by bolts *m*. *m'* represents pintles 100 connecting a door K to one of the links M.

Spouts E are curved, as at N, and provided, on the inside thereof, with valveways or seats *n*; and O, (Fig. 3), is a valve arranged to co-act with valveways *n*. When 105 slide valve O is in position to close the aperture in valveways or valve seats *n*, the lower end of spout E is separated from the upper

end thereof (see Fig. 3) and when said spout is in the position indicated by broken lines in said Fig. 3, said valve is seated by means of rod P which is attached at its lower end to door K, as by eyebolt p and casting p'. Q are agitators on connection P. When, in the operation of the device as herein-after described, the valve O is seated and the lower end of spout E is open, the sand which has settled in the lower end of said spout, is started toward falling from the spout by said agitators Q.

In Fig. 1 one of the spouts E is illustrated in position with the lower end thereof closed by its door K and the other (the right hand one as viewed) is illustrated as turned on its pintle away from the door K thereby opening said lower end so that sand which is contained in said spout adjacent to said door may fall therefrom, and X represents sand flowing from said spout.

The connection P is arranged so that when the lower end of spout E is moved against and closed by door or cover K the valve O is off its seat and sand settling in said spout falls through opening or aperture e' and valve seat n on to the door or cover K; and as said spout is turned on its pivot to move the lower end thereof away from said door or cover K said valve O is moved longitudinally on its seat to close said aperture. The weight H is adjustably secured on member F to close door K against the pressure of water thereon and so that when a determined quantity of sand at the lower end of spout E has displaced the water therein, the added weight caused by said displacement will automatically turn said spout, raising said weight, opening the door or cover K and closing the valve O. This last named operation is to limit the flow of water along with the falling sand from said spout.

R is a perforated shelf in tank A and r is a vertical partition. By means of perforated shelf R and partition r a receiving receptacle for water holding sand in suspension from conduit or pipe B is obtained, said water and sand being discharged from said receptacle into tank A through the perforations in said shelf, thereby breaking up any current which might otherwise be formed from the receiving to the discharge or overflow end of said tank A.

The operation of the apparatus is:—

A flow of water and sand being discharged into tank A the sand which is suspended in said water will settle in the lower end of spout E and when a determined quantity of sand is in said spout the weight thereof, being greater than the weight of the water displaced thereby, will cause said spout to move pivotally away from the door or cover thereof, the valve O will be closed, and the sand in said spout below said valve will fall therefrom. No appreciable quantity of

water will follow said sand. The water in tank A will rise to over-flow therefrom, and said water will be substantially clear, the sand therein having settled therefrom to be ultimately deposited in spouts a and E.

By using a stationary tank provided with a number of movably mounted settling spouts arranged to receive the sand which settles from the water in said tank, and to be moved by gravity to discharge the sand therein and, having discharged said sand to be returned, by gravity to their initial positions said tank may be of sufficient size to prevent the over flow of water carrying any sand therewith; and by placing a valve to separate the portion of the settling spout which contains sufficient sand to automatically move said settling spout with means to automatically close said valve as said settling spout moves, I prevent the discharge of any appreciable volume of water along with said sand from said large tank.

In practice the weight H is adjusted so that some sand will be on valve O as the settling spout moves away from its cover or doors.

I claim;

1. In a sand settling box, a tank, down spouts from said tank, movably mounted settling spouts arranged to receive sand from said down spouts, weights arranged to hold said settling spouts in determined inclined positions, covers mounted on the discharge ends of said settling spouts, and means to hold said covers to open and close said discharge ends as said settling spouts are moved by gravity away from and back to said determined position.

2. In a sand settling box, a tank, a receptacle provided with a foraminated bottom positioned in said tank, means to direct water and sand into said receptacle, down spouts from said tank, movably mounted settling spouts arranged to receive sand from said down spouts, weights arranged to hold said settling spouts in determined inclined positions, covers mounted on the discharge ends of said settling spouts, and means to hold said covers to open and close said discharge ends as said settling spouts are moved by gravity away from and back to said determined position.

3. In a sand settling box, a tank, down spouts from said tank, movably mounted settling spouts arranged to receive sand from said down spouts, valve seats in said settling spouts and valves arranged to co-act with said seats, weights arranged to hold said settling spouts in determined inclined positions, covers mounted on the discharge ends of said settling spouts, connections between said covers and said valves and means to hold said covers to open and close said discharge ends and seat and unseat said valves as said settling spouts are moved by

gravity away from and back to said determined positions.

4. In a sand settling box, a tank, a receptacle provided with a foraminated bottom positioned in said tank, means to direct water and sand into said receptacle, down spouts from said tank, movably mounted settling spouts arranged to receive sand from said down spouts, valve seats in said settling spouts and valves arranged to co-act with said seats, weights arranged to hold said settling spouts in determined inclined positions, covers mounted on the discharge ends of said settling spouts, connections between said valves and said covers, agitators on said connections, and means to hold said covers to open and close said discharge ends and move said connections, agitators and valves, as said settling spouts are moved by gravity away from and back to said determined positions.

5. In a sand settling box, a tank, down spouts from said tank, journal bearings attached to the bottom of said tank, settling spouts mounted on said journal bearings, the upper ends of said settling spouts being closed and said closed ends provided with apertures, flanges around said apertures, tubular connections of flexible material attached to said flanges and to said down spouts, pipes attached to the discharge ends of said down spouts and extending through

said apertures into said settling spouts, valve seats in said settling spouts and valves arranged to co-act with said seats, weights 35 arranged to hold said settling spouts in determined inclined positions, covers mounted on the discharge ends of said settling spouts, connections between said covers and said valves and means to hold said covers to 40 open and close said discharge ends and seat and unseat said valves as said settling spouts are moved by gravity away from and back to said determined positions.

6. In a sand settling box, a tank, a receptacle provided with a foraminated bottom positioned in said tank, means to direct water and sand into said receptacle, down spouts from said tank, movably mounted settling spouts arranged to receive sand from 50 said down spouts, flexible connections between the settling spouts and the down spouts to prevent the flow of water therefrom, means arranged to hold said spouts in determined inclined positions, covers 55 mounted on the discharge ends of said settling spouts, and means to hold said covers to open and close said discharge ends as said settling spouts are moved by gravity away from and back to said determined position. 60

JOHN F. REINERT.
